UNITED STATES PATENT OFFICE.

EDWARD C. COLLINS, OF TAUNTON, MASSACHUSETTS.

BRAKE-HANDLE FOR CARS.

SPECIFICATION forming part of Letters Patent No. 611,058, dated September 20, 1898.

Application filed January 5, 1898. Serial No. 665,687. (No model.)

To all whom it may concern.

Be it known that I, EDWARD C. COLLINS, of Taunton, in the county of Bristol and State of Massachusetts, have invented certain new and useful Improvements in Brake-Handles for Cars, of which the following, taken in connection with the accompanying drawings, is a specification.

My invention relates to brake-handles for cars; and it consists in certain novel features of construction, arrangement, and combination of parts, which will be readily understood by reference to the description of the accompanying drawings, and to the claims hereto appended, and in which my invention is clearly pointed out.

Figure 1 of the drawings is a plan of a brake-handle embodying my invention with the pawl engaging the ratchet in condition to rotate the brake-shaft. Fig. 2 is a side elevation of the same. Fig. 3 is an end elevation looking toward the left of Fig. 2. Fig. 4 is a section on line $x-x$ on Fig. 2. Fig. 5 is a partial plan showing the two parts of the handle in a position relative to each other to permit the pawl to be retracted from engagement with the ratchet-teeth on the brake-shaft, and Fig. 6 is an elevation of a small portion of the upper end of the brake-shaft 30 with the handle removed.

In the drawings, A is a portion of the brake-shaft, provided at its upper end with the journal a and with a series of ratchet-teeth b , as shown in Fig. 6 and in dotted lines in Figs.

35 1 and 5.

The brake-handle is made in two parts B and B', hinged together by the steel pin c , as shown in Figs. 1, 2, and 4. The part B' is fitted to the upper end of the shaft A, so as 40 to be revoluble thereon, and is prevented from being lifted therefrom by the set-screw d set therein and engaging the annular groove e , formed in said shaft, as shown in Figs. 2 and 6. The part B' is provided with the stop-45 shoulders f and f' and the ears g and g' , and has formed therein a rectangular mortise g^2 , extending from the shoulder f toward the axis of the shaft A, in which is fitted, so as to be movable endwise therein, the pawl-plate h , 50 arranged to engage by its inner end the ratchet-teeth b , and when so engaged its outer

end is flush with the face of the shoulder f , as shown in Fig. 4. The part B of said handle is provided with the ear i and the shoulders j and j' , as shown in Fig. 4. The fulcrum-pin c extends through the ear i of the part B of the handle only part way through the ear g' of the part B' and extends upward only two-thirds through the ear g , the upper part of the hole through said ear being closed 60 by the screw-plug C , provided with a convex head of sufficient size to cover the openings between the shoulders f and j and between the shoulders f' and j' , as viewed in plan.

The operation of my invention is as follows: 65 When it is desired to apply the brake, the motorman or brakeman moves the handle B B' in the direction indicated by the arrow on Fig. 1, the first effect of which is to move the part B about the pin c until the shoulders f and j come in contact, said shoulders having previously been separated, as indicated in Fig. 5, which first movement causes the pawl h to engage one of the teeth b of the ratchet on the upper end of the shaft A, and a continuation of the movement of the handle will cause a movement of said shaft about its axis in the same direction sufficient to apply the 70 brake to the wheel. When it is desired to remove the brake from contact with the wheel, 75 the operator moves the part B of the handle about the pin c until the shoulders f' and j' come in contact with each other, then moves both parts of the handle in the direction until the inner end of the pawl h is moved about 80 the shaft A a distance equal to the distance between the teeth b on said shaft, which movement will cause the said pawl to be moved outward and disengaged from the ratchet-teeth when the operator disengages the locking-pawl on the floor of the car-platform from 85 its ratchet, when the strain of the brake-chain will rotate the shaft A, and the tension on the 90 brake will be released.

What I claim as new, and desire to secure 95 by Letters Patent of the United States, is—

1. A brake-handle made in two parts connected together by a vertical hinge-pin, and each part provided with two stop-shoulders constructed and arranged to permit only a 100 limited movement of one of said parts about said hinge-pin, and a pawl, to engage said

ratchet, carried by the hub-section of said handle, and acted upon by the other section of said handle to cause said engagement.

2. A brake-handle made in two parts connected together by a stop hinge-joint, the axis of the hinge-pin of which is vertical, said stop-joint being constructed and arranged to permit only a limited movement of one of said parts about said hinge-pin in either direction; 5 in combination with a brake-shaft provided at its upper end with a series of ratchet-teeth and fitted to and revoluble in a bearing in the hub portion of said handle; and a pawl-plate fitted to and movable endwise in a bearing in 10 said hub portion of said handle in position to be acted upon by the stop-shoulder of the other portion of said handle, at its outer end, and to engage said ratchet-teeth by its inner end. 15 3. The combination of the brake-shaft A provided with the ratchet-teeth *b* and annular groove *e*; a brake-handle composed of the two parts B and B' connected together by the vertical hinge-pin *c* and said parts being provided with the stop-shoulders *j*, *j'* and *f*, *f'* respectively, and the part B' with the oblique 20 25

mortise *g*; the pawl-plate *h*; the set-screw *d* engaging the groove *e*; and the screw-plug C all constructed arranged and operating substantially as described.

4. In combination with a brake-shaft provided with a series of ratchet-teeth upon its upper end; a brake-handle made in two parts connected together by a stop hinge-joint and mounted loosely upon the upper end of said shaft; and a sliding pawl fitted to and movable endwise in a bearing in the hub portion of said handle in position to be moved into engagement with said ratchet-teeth by the movement of the outer portion of said handle 35 about its hinge-pin in one direction, and to be disengaged from said teeth by the action of a tooth upon its inner end when the handle is moved in the opposite direction.

In testimony whereof I have signed my name to this specification, in the presence of two subscribing witnesses, on this 31st day of December, A. D. 1897.

EDWARD C. COLLINS.
